Primary Examiner—Mitchell Siegel*(74) Attorney, Agent, or Firm*—Banner & Witcoff, Ltd.(57) CLAIM

The ornamental design for a portion of a golf club head, as shown and described.

DESCRIPTION

FIG. 1 is a rear perspective view of a portion of a golf club head showing my new design;

FIG. 2 is a rear view thereof;

FIG. 3 is a bottom view thereof;

FIG. 4 is a heel end view thereof; and,

FIG. 5 is a cross-sectional view taken along the line 5—5 of FIG. 2.

The broken line showing of the remainder of the golf club head is for illustrative purposes only and forms no part of the claimed design.
